(57) **CLAIM**

The ornamental design for an PDA instrument support device, as shown and described.

DESCRIPTION

The PDA instrument support device is used for supporting PDA instruments, (hand-held Personal assistants, PDAs) by way of a suction cup on smooth surfaces such as windshields dashboards or smooth mounting plates in positions convenient for the user.

FIG. 1 is a front view of an PDA instrument support device; FIG. 2 is a rear view of the PDA instrument support device shown in FIG. 1;

FIG. 3 is a perspective rear side view of the PDA instrument support device shown in FIG. 1.

The side views are identical except for being mirror-reversed.
